UNITED STATES PATENT OFFICE.

ALBERT DÖRING, OF DRESDEN, GERMANY, ASSIGNOR TO AKTIENGESELLSCHAFT, VORMALS SEIDEL & NAUMANN, OF DRESDEN, SAXONY, GERMANY.

BOBBIN HOLDER-CASE FOR SEWING-MACHINES.

SPECIFICATION forming part of Letters Patent No. 709,886, dated September 30, 1902.

Application filed June 12, 1902. Serial No. 111,384. (No model.)

To all whom it may concern:

Be it known that I, ALBERT DÖRING, a subject of the King of Saxony, residing at Dresden, Germany, have invented certain new and useful Improvements in Bobbin Holder-Cases for Sewing-Machines, of which the following is a clear, full, and exact specification.

The present invention relates to an improved construction of sewing-machine bobbin holder-case by means of which the two halves of the case can be closed simply and effectively, the said halves for the purpose of removal or insertion of the bobbin having to be turned back. Means are also provided whereby the bobbin is prevented from sliding down on the opening of the case. This is effected by the hinged half of the casing being held against the rigid half by a catch device—that is to say, it is locked by a bolt, a fork, moreover, coming into operation to hold the bobbin on disengagement of the bolt.

In the annexed drawings one form of construction of my invention is illustrated.

Figure 1 is an elevation of the device. Fig. 2 is a cross-section taken through Fig. 1. Fig. 3 is an end view, the bolt being in operation. Fig. 4 is a like view to Fig. 1, the device being here shown open. Fig. 5 is an end view of Fig. 4. Fig. 6 is a plan view of Fig. 1. The bobbin-case is carried by an arm *a*, one end of which is provided with a hole whereby it may be rigidly or rotatably mounted on the machine-frame, while the other end constitutes the rigid half *b* of the bobbin-case. The second half *c* is hinged to the drum-arm *d* of the arm *a*, so that it can be turned back.

In the center of the bobbin half *c* is pivoted a lever *e*, one arm *e'* of which serves as handle, while the other can be turned as bolt

before the arm *d* when the case *e* is to be closed. The surface on which the catch slides is slightly inclined for the purpose of enabling tight closing of the parts. To the part *c* a fork *g* is hinged at *f*, the two prongs *h h* of which take over the edge of the bed of the bobbin and over the latter itself when the hook is turned. This occurs simultaneously with disengagement of the bolt *e*, the latter sliding from the surface against which it has been reposing. For this purpose on the axis of the lever *e* is mounted a disk *i*, having a cam-surface *k*, which presses the fork in the direction of the bobbin against the action of a spiral spring *l*, located at the hinge, which spring presses back the fork again when the lever is turned over in opposite direction—*i. e.*, when the case is again closed. When the bobbin-case is closed, the thread can run freely over the bobbin. On being opened, however, the two hooks *h h* of the fork *g* come below the bobbin and prevent its sliding down.

Having thus described my invention, what I claim as new, and desire to secure by Letters Patent, is—

A sewing-machine bobbin-case carrier, comprising a double-armed pivotal catch one arm of which constitutes a bolt for the movable half of the case, a cam device actuated by the said catch, and a hinged fork operated by said device, for preventing the bobbin sliding down on opening the case, substantially as described.

In witness whereof I have hereunto set my hand in presence of two witnesses.

ALBERT DÖRING.
